UNITED STATES PATENT OFFICE.

CHARLES BELLHOUSE, OF VANCOUVER, BRITISH COLUMBIA, CANADA.

SET-UP FOR KNITTING MACHINES.

Application filed June 26, 1922. Serial No. 570,801.

To all whom it may concern:

Be it known that I, CHARLES BELLHOUSE, of the city of Vancouver, in the Province of British Columbia, Canada, have invented certain new and useful Improvements in Set-Ups for Knitting Machines, of which the following is the specification.

My invention relates to improvements in set-ups for knitting machines and the object 10 of the invention is to devise means for saving time in setting up the knitting on the machine, for insuring the starting stitches being perfectly even, and for preventing the set-up from being inadvertently dislodged from any part of the work during 15 the operation of the knitting machine.

My invention consists essentially of a slotted circular body having a plurality of swinging arms radiating therefrom and an 20 endless cord connecting the outer ends of the arms together as will be more particularly described in the following specification, in which:

Fig. 1 is a sectional view of a knitting machine cylinder showing my set-up in position for starting the work.

Fig. 2 is a fractional sectional view of the cylinder showing the set-up cord engaging the needles and the lead thread being started 30 onto the machine.

In the drawings like characters of reference indicate corresponding parts in each figure.

1 represents a knitting machine cylinder. 35 2 is a plurality of needles slidably mounted in vertical grooves 3 of the cylinder, all of which parts are common to knitting machines of the cylinder type.

4 is a circular body having a circular recess 5 in its upper face, a circular boss 6 on its lower face, and an annular rim 7, having a semi-circular groove 8 around its outer periphery intermediate its depth and a plurality of slots 9 extending vertically 45 downwards from the upper face of the body. 10 is a plurality of radially disposed arms each having an eye 11 at its outer end and an extension 12 passing inwardly through one of the slots 9 as will hereinafter 50 be more fully explained. The arms 10 are fulcrumed as at 13 upon a wire pivot 14, which pivot is formed as a ring encircling the body 4 and lying within the semi-circular groove 8. 15 is an endless cord passing 55 through the eyes 11 of the arms 10. 16 is a circular member having a groove 17

around its periphery into which the extensions 12 of the arms 10 project.

18 is a rod attached to the member 16 and extending downwardly through the boss 6 of the body 4 through which it is allowed free vertical movement. The lower end of the rod 18 is formed as a ring or hook 19, that tension weights, (not shown), may be conveniently attached thereto. 20 is a circular member secured intermediately of the length 60 65 of the rod 18 for the purpose of receiving a slotted weight, (not shown).

21 is a pair of upstanding legs of resilient material attached to the upper face of the 70 member 16 and slightly spread apart at their upper ends as at 22 to form a clip to receive the primary knitting cotton 23 and also for the purpose of forming a projection by which the set-up may be held from 75 above the knitting machine cylinder.

Having described the various parts of my invention, I will now briefly describe the operation of the same.

The machine is set so that all the needles 80 2 project above the top of the knitting machine cylinder as shown in Fig. 1. The set-up is lifted by the clip 21 allowing the body 4 to slide vertically downwards upon the rod 18, thereby causing the arms 10 to lie 85 in a substantially horizontal plane. The set-up is then placed into the cylinder, the arms lying between the needles and extending beyond the periphery of the cylinder, 90 the cord 15 encompassing all the needles.

On the set-up being released, the member 16 slides downwardly into the recess 5 while the body 4 is also descending within the cylinder, the arms 10 assume an inclined position and their outer ends are withdrawn 95 from between the needles, so that the cord 15 is automatically looped evenly on the several needles of the machine. This sets the device in position ready for the commencement of the initial stitches when it suffices to weight the rod 18 with superimposed weights as desired to provide the necessary tension for the work. The initial stitches are usually made with a strong thread 23, the end of which is threaded through the yarn carrier of the machine (not shown) and inserted into the clip 21, as shown. The operation of the machine causes the thread 23 to form loose even 100 stitches onto the endless cord 15, which cord 105 is released from the various needles as they each descend within the grooves 3. When a 110

few rows of stitches are made with the thread 23, a yarn is substituted for the thread and the work continued.

On the completion of the knitting, the 5 initial stitches are cut and withdrawn from the cord 15 of the set-up and the finished work when the set-up is ready for re-use.

It will be seen that I have devised a set-up which is automatic in action, which will 10 save considerable time in setting up work on a knitting machine and one which enhances the quality of the work by producing a perfectly even stitch at the commencement of the knitting.

15 What I claim as my invention is:

1. A set-up device for knitting machines provided with the usual cylinder and needles, comprising an endless set-up cord adapted to extend around at the outside of

20 the needles and adapted to receive the initial stitches of the work, and means suspended within the cylinder and from such cord to hold said cord in tension in inwardly looped formation between each pair of needles.

25 2. A set-up device for knitting machines, provided with the usual cylinder and needles, comprising a circular body, an endless cord extending around the outside of the needles and adapted to receive the initial 30 stitches of the work, and radially disposed arms pivotally connected to and extending from said cord between each needle and upon which the circular body is suspended.

35 3. A set-up device for cylindrical knitting machines comprising a circular body located within the cylinder of the machine, arms pivoted thereto and radiating therefrom in a normally upward inclined direction, an endless cord adapted to surround the needles 40 and connecting the outer ends of the arms together, and means for automatically

spreading the arms to assume a horizontal position to spread the cord by the raising of the aforesaid circular body.

4. A set-up device for cylindrical knitting 45 machines comprising a circular body located within the cylinder of the knitting machine, a cord extending around the outside of the knitting machine and the needles thereof, arms pivotally connected to the body and radiating therefrom and connected at their free ends to the cord, and means carried by the body for simultaneously spreading the arms outward towards a horizontal position as the body is lifted. 55

5. A set-up device for cylindrical knitting machines comprising a circular body, arms pivotally connected thereto, and radiating therefrom, a cord connecting the free ends of the arms together, a member carried by 60 the circular body and adapted to have vertical movement in relation thereto, and a pivotal connection between the inner ends of the arms and such movable member.

6. A set-up device for cylindrical knitting 65 machines comprising a circular body having a surrounding edge flange provided with edge notches, arms pivotally mounted in the edge notches intermediately of their length, a cord connecting the free ends of the arms 70 together, a rod mounted within the body to move vertically, a circular member carried thereby provided with an annular edge groove into which the inner ends of the aforesaid arms extend, and a cord clip device carried by the grooved member. 75

Dated at Vancouver this 27th day of May, 1922.

CHARLES BELLHOUSE.

Witness:

J. J. JOHNSTON.
